W. F. BLAKE,
BELL AND BALL TOY,
APPLICATION FILED AUG. 25, 1919.

1,368,386.

Patented Feb. 15, 1921.

William F. Blake Inventor

UNITED STATES PATENT OFFICE.

WILLIAM F. BLAKE, OF TOLEDO, OHIO.

BELL AND BALL TOY.

1,368,386.

Specification of Letters Patent. Patented Feb. 15, 1921.

Application filed August 25, 1919. Serial No. 319,691.

To all whom it may concern:

Be it known that I, WILLIAM F. BLAKE, a citizen of the United States, residing at Toledo, in the county of Lucas and State of Ohio, have invented a new and useful Bell and Ball Toy, of which the following is a specification.

My invention relates to bell and ball toys in which the same are attached to a handle; 10 and the objects of my invention are, first to provide a toy for small children which is light, simple, and amusing; and second, to provide a toy having a handle to which is attached a bell and a ball so they cannot 15 be easily lost.

I attain these objects by the mechanism illustrated in the accompanying drawing, in which—

Figure 1 is a view of the toy as a whole; 20 Fig. 2, a detail view showing the method of attaching the bell and ball to the handle; and Fig. 3, detail view of the bell showing the sounding slots.

Similar numerals refer to similar parts 25 throughout the several views.

Referring to Fig. 1, the figure 1 indicates the handle made of wood or other material and 2 a spherical bell attached to the end of handle 1. 3 shows the collets through 30 which the body of a pin or nail passes and thus bell 2 is held in alinement with the handle, 4 is an opening in side of the bell for inserting anchor 6 which is placed to 35 one side of the axis of the bell to facilitate movement, thereby causing the bell to ring. 5 is an endless elastic band with one end looped over anchor 6 and the other over the eye of swivel device 9 which is inserted in one side of the hollow rubber ball 7, thus 40 connecting the ball with handle 1. The swivel eye device 9 has the prongs 12 inserted in the ball 7 and crossed at such an angle that when tension is placed on the projecting eye 9 the prongs 12 are forced to press 45 outward and upward on the sides of the ball 7 and so cannot be pulled out. The loose balls 8 act as a clapper in bell 2. The sounding slots 10 are shown in Fig. 3, also one of the collets 3; the sleeve 11 of the other collet

is inserted at the intersection of the slots 10 50 and so keeps bell 2 from sliding out of position by way of the sounding slots 10; thus collets 3 keep bell 2 in vertical alinement with handle 1, yet allow the bell to rotate and chime. 55

In the operation of my invention, a child grasps the handle 1 and bounces the ball 7 on the ground, wall, floor, chair, etc. The elastic band 5 will stretch and bring the ball back, while the clapper 8 rings or chimes 60 against the sides of bell 2, thus amusing the child. This toy can be used as a rattle or the child can whirl the handle and as the ball is attached at one side of the axis of the bell it will readily whirl around describing 65 a wheel or circle.

Having thus described my invention, what I claim as new and desire to secure by Letters Patent, is:

1. In a bell and ball toy, the combination 70 of a handle with a bell rotatably attached to the handle and an anchor projecting from the periphery of the bell and at one side of the axis of the bell with an endless elastic band looped over said anchor and the 75 other end of said band looped over a swivel eye in a hollow rubber ball to cause the bell to rotate on the handle.

2. A toy of the class described, comprising 80 a handle, a bell rotatably mounted on said handle, a flexible member pivotally secured at one end to said bell eccentric to the axis thereof, and a ball suspended by said flexible member and adapted to swing the latter to impart rotative movement to said bell. 85

3. A toy of the class described comprising 90 a handle, a bell rotatably mounted on said handle, an anchorage member engaged with said bell eccentric to the axis thereof, an endless elastic band engaged with said anchorage member, and a ball carried by said band and adapted to swing therewith to rotate said bell.

WILLIAM F. BLAKE.
